United States Patent Office

Des. 187,859
Patented May 10, 1960

187,859

PORTABLE COOLER FOR AUTOMOBILES

Lawrence W. Bonzer, Long Beach, Calif., assignor to
G & B Manufacturing Co., Inc., Long Beach, Calif.,
a corporation of California

Application December 15, 1959, Serial No. 58,676

Term of patent 14 years

(Cl. D14—6)

Fig. 1.

Fig. 2.

Figure 1 is a three-quarter top front perspective view of a portable cooler for automobiles showing my new design;

Figure 2 is a front elevational view of said cooler;

Figure 3 is a three-quarter bottom rear perspective view of said cooler; and

Figure 4 is a side elevational view of said cooler.

The undisclosed side of the cooler is substantially the same in appearance as the side shown.

I claim:

The ornamental design for a portable cooler for automobiles, substantially as shown and described.
